(57) **CLAIM**

The ornamental design for a cleaning head, as shown and described.

DESCRIPTION

FIG. 1 is a bottom isometric view of a cleaning head showing our new design;

FIG. 2 is a left side elevation view thereof;

FIG. 3 is a bottom plan view thereof;

FIG. 4 is a right side elevation view thereof;

FIG. 5 is a front elevation view thereof;

FIG. 6 is a rear elevation view thereof;

FIG. 7 is a bottom isometric view of a second embodiment thereof;

FIG. 8 is a left side elevation view of FIG. 7;

FIG. 9 is a bottom plan view of FIG. 7;

FIG. 10 is a right side elevation view of FIG. 7;

FIG. 11 is a front elevation view thereof of FIG. 7; and,

FIG. 12 is a rear elevation view of FIG. 7.

FIGS. 7-12 present the same views of the same embodiment as shown in FIGS. 1-7, respectively, in an alternate drawing style.

The broken lines are for illustrative purposes only and form no part of the claimed design.
